SAFETY BUCKLE

Siegmund Strauss, Vienna, Austria

Application March 17, 1937, Serial No. 131,278
In Austria April 4, 1935

7 Claims. (Cl. 24—178)

My invention relates to buckles for straps and belts and has for its object to provide a buckle which automatically releases the end of the strap, when the pull exerted upon said strap exceeds a certain predetermined value.

My safety-buckle may be used in bindings for skis or for other purposes where it is desired that the strap connection is automatically released if excessive force is exerted upon the same. Thus, for instance, in skiing, bone-fractures or other casualties and damages to the ski-binding may be avoided.

With these objects in view, I provide in my safety buckle two holding elements for the perforated strap, e. g. a rest and a tongue adapted to pass through the perforations of the strap and normally overlying said rest. The two holding elements are movable against each other relative to the resilient force of a spring or the like whereby the tongue is disengaged from said rest and the strap is released, if the pull exerted upon the strap exceeds a certain predetermined value.

My invention also aims at resetting means in a safety buckle of this kind, which enable the user to easily refasten the strap in the buckle.

My invention further aims at providing a safety buckle of this kind which may be manufactured at low expense and which may be easily assembled and disassembled to interchange the spring and other parts of it.

Other features of my invention will appear from the following detailed description with reference to the accompanying drawing, in which Fig. 1 is a plan view of an embodiment of the safety buckle according to the invention in its normal position,

Fig. 2 is a side elevation of the buckle, also in its normal position,

Fig. 3 is a side elevation of the buckle in the position which it attains if the strap buckled into it is subjected to a heavy pull,

Fig. 4 shows the buckle in the same position as Fig. 3 after the strap has been released,

Fig. 5 shows in a side elevation the manner in which the tongue is restored to normal position,

Fig. 6 represents in a plan view a modification of the safety buckle with interchangeable spring.

The frame of the buckle is formed, as shown by Figs. 1 to 6, by side pieces 1, a bridge or rest 2 and a plate 3. These parts may be punched in one single piece from sheet metal, the plate 3 being formed by bending the metal at a right angle. The plate 3 has a slot allowing a metal

strip 6 to pass it with clearance whereby said strip is slidable, in longitudinal direction and also swingable to some extent. The end of the strip 6 is rolled up to form an eye accommodating the pin 9 of a bail 10. The latter serves to attach the fixed end of the strap (not shown) in the usual manner, for instance on the roller 11. The bail 10 has two cams 12, the purpose of which will be described later. The other end of the metal strip 6 forms the tongue 4 of the buckle. A slotted plate 15 rides on the strip 6 and bears upon shoulders or extensions 5 of the strip 6. A strong pressure spring 8 is arranged between the plates 3 and 15 which spring may have an initial tension in the normal position of the buckle.

The perforated end 14 of the strap is buckled in the usual manner, as shown in Fig. 2. If a pull is exerted upon the strap, the frame 1, 2, 3 moves together with the end 14 relatively to the other part, as shown in Fig. 3. During this movement, the spring 8 is compressed. If the pull exceeds a maximum, which may be predetermined at will by choosing a spring of appropriate strength and by varying the distance a in Fig. 1, i. e. the overlapping between the rest 2 and the tongue 4, the tongue 4 slides off the rest 2, releases the end of the strap 14 and assumes a position on the opposite side of the rest 2, as shown in Fig. 4.

In order to be able to fasten the end of the strap 14 again, it is necessary to reset the tongue to its normal position shown in Fig. 1. This would be very difficult against the action of strong spring 8, because this spring has to be compressed to reset the tongue. The cams 12 serve to compress this spring without undue effort by cam action, if the bail 10 is rotated for about 90° with respect to the frame 1, 2, 3, as shown in Fig. 5.

In the modification shown in Fig. 6 the plate 15 is secured to the tongue by means of a pin 13, which is held in a hole in the strip 6 under the action of the compressed spring 8. The pin 13 may be removed and the buckle may be dismounted, for instance in order to interchange the spring 8 and thereby adjust the force of the pull necessary to release the safety buckle.

What I claim is:—

1. A buckle comprising a frame, a rest forming part of said frame, a tongue adapted to engage a strap and to bear upon said rest, said tongue forming part of a strip passing with clearance through a slot in a plate of said frame opposite to said rest, a retaining element on said tongue, 50

- resilient means arranged between said frame and said retaining element on said tongue and cam means rotatably attached to said strip outside of said frame and adapted to compress said resilient means.
5. 2. A buckle comprising a frame, a rest forming part of said frame, a tongue adapted to engage a strap and to bear upon said rest, said tongue forming part of a strip passing with clearance through a slot in a plate of said frame opposite to said rest, a retaining element on said tongue, resilient means arranged between said frame and said retaining element on said tongue, an eye formed on the end of said strip outside of said 10 frame, a pin passing through and rotatable within said eye and bearing a strap, and cams forming part of said loop and cooperating with the slotted plate of the frame to compress said resilient means.
15. 3. A buckle comprising a frame, a rest forming part of said frame, a tongue adapted to engage a strap and to bear upon said rest, said tongue forming part of a strip passing with clearance through a slot in a plate of said frame opposite to said rest, means on said strip outside of said frame for attaching a strap, a second slotted plate riding on said strip within said frame, a removable cross pin securing said latter slotted plate to said strip, and a helical compression 20 spring surrounding said strip and interposed between the slotted plate of said frame and said second slotted plate, said spring having an initial tension in the normal position of the buckle.
25. 4. A buckle comprising, a frame, a rest integral with said frame, a tongue swingable and longitudinally displaceable in said frame, the free end of said tongue normally bearing upon said rest, a fixed retaining element on said tongue and resilient means interposed between said frame and said retaining element on said tongue to retain the latter in its normal position, said resilient means permitting withdrawal of said tongue to a position free of said rest under a pull exceeding a predetermined maximum.
30. 5. A buckle, as claimed in claim 4, wherein said resilient means consists of a helical compression spring having an initial tension in the normal position of the buckle.
35. 6. A buckle for connecting two strap ends, comprising, a frame, a transverse rest forming part of said frame, a tongue adapted to engage one of said strap ends and normally bearing upon said rest, said tongue being swingable and longitudinally displaceable within said frame and having means to attach the second strap end to said tongue at a longitudinally fixed point thereof, a retaining element fixed on said tongue, and resilient means interposed between said frame and said retaining element on said tongue to retain the latter in its normal position, said resilient means permitting withdrawal of said tongue to a position free of said rest and disengagement of said first mentioned strap end, when the pull exerted on said second strap end exceeds a predetermined maximum.
7. A buckle, as claimed in claim 4, in which said tongue consists of a strip passing with clearance through an opening in a plate of said frame opposite said rest.
